UNITED STATES PATENT OFFICE

CLARENCE F. GILCHRIST, OF TOLEDO, OHIO, ASSIGNOR, BY MESNE ASSIGNMENTS, TO THE ELECTRIC AUTO-LITE COMPANY, OF TOLEDO, OHIO, A CORPORATION OF OHIO

DRIVING MECHANISM

Application filed July 22, 1918, Serial No. 246,188. Renewed July 23, 1928.

This invention relates to a driving mechanism for use in the starting system of an internal combustion engine. More particularly considered, the invention comprises an automobile screw gearing applicable in the gear train intermediate the electric starting motor and internal combustion engine.

The principal object of this invention is to provide a driving mechanism intermediate the electric motor and engine which has flexibility and elasticity, and in which there is no spring or similar elastic member in the direct line of power transmission.

Another object is to provide a type of gearing in which the driving connection and disconnection is made in an entirely automatic way.

Another object is to utilize a gearing unit which will automatically take care of variations in engine cylinder compression.

Further objects of this invention relate to economies of manufacture and details of construction as will hereinafter appear from the detailed description to follow. I accomplish the objects of my invention in one instance by the devices and means described in the following specification, but it is evident that the same may be varied widely without departing from the scope of the invention as pointed out in the appended claims. A structure constituting one embodiment of my invention, which may be the preferred, is illustrated in the accompanying drawing forming a part thereof, in which:

Fig. I is a longitudinal sectional view taken through the gearing unit showing it in its disconnected position.

Fig. II is a view similar to Fig. I but showing the gearing unit in its connected position, certain parts being shown in elevation.

Figures III, IV and V are cross sectional views taken respectively on the lines III-III, IV-IV and V-V of Fig. I.

Similar reference numerals refer to similar parts throughout the several views, and the cross sections are taken looking in the direction of the arrows.

As illustrated, the driving mechanism is shown as forming part of an electric starting motor 1, having a driving shaft 2, the outer

end 3 of which is threaded for a purpose hereinafter described. Mounted upon the shaft 2, and adapted for axial movement thereupon, is a sleeve 4 which is threaded for a portion of its length, as indicated at 5. Internally threaded, so as to mesh with the thread upon the sleeve, is a pinion 6, which preferably has a counter-weight 7, and which is offset longitudinally at 8. In order to hold the pinion at the outward limit of its movement, there is utilized a tensioning spring 9, which is mounted upon a pin 10, placed intermediate the offset portion of the counter-weight and the sleeve. There is a collar 11 on the pin, and between this collar and the counter-weight, the spring exerts pressure so that when the pin is outside the outer thread the pinion is held from inward movement until a sufficiently large force is applied thereto, thereby keeping the pinion in proper adjustment relative to the sleeve 4.

The pinion is adapted to have axial movement along the sleeve, so as to permit its engagement with the gear 12, which gear is directly connected to the crank shaft of the engine, and in the arrangement commonly used forms the fly-wheel of the engine. Upon the inner end of the sleeve is a stop 13 for limiting the movement of the pinion when it is in mesh with the gear 12.

As shown in Figure V of the drawing, the sleeve 4, at its outer end, is slotted in such a way as to form four slots 14, situated at right angles to each other around the circumference of the sleeve. Adapted to have screw thread engagement with the threaded portion of the shaft of the motor, is a nut 15 of circular cross section as indicated in Figure III. Keyways 16 are cut in this nut, and keys 17 inserted, and these keys are adapted to have axial movement in extended keyways 18, cut on the interior of a tubular casing 19, so that motion may be transmitted continuously in the direction of rotation of the nut, simultaneously with axial movement thereof. The casing 19 has at its opposite end an inwardly extending flange 20 which has four inwardly extending lugs 21 engaging in the slots 14 of the sleeve. A washer 22 is secured over the 190

sleeve so as to prevent inward movement of the casing 19.

In the annular space between the casing and the sleeve is a coil spring 23 whose one end abuts against the flange 20 and whose other end abuts against the nut 15 and is adapted to retard the movement of the units in an inward direction. Outward movement of the nut 15 is prevented beyond the terminal of the shaft by a washer 24 and nut 25, and the inner movement of the nut 15 is limited by the end of the sleeve 4 which extends within the casing to a point adjacent the inner end of the keyways 18.

In the operation of this driving mechanism, power is transmitted from the motor through the shaft 2, to the nut 15. Inasmuch as there is a screw connection between the motor shaft and nut, there will be a tendency of the nut to screw inwardly on the shaft, but opposition of this movement is afforded by the spring, and inasmuch as, initially, there is no load on the pinion 6, inward motion of the nut is practically absent. From the nut, transmission is extended through the guide casing 19 to the sleeve 4, so that there is rotation of all movable parts upon the shaft, with the exception of pinion 6, which, because of its inertia, moves without rotation axially into mesh with the gear. As soon as the pinion has come into complete mesh with the gear wheel 12, and is prevented from further axial movement by the stop 13, the pinion will immediately attempt to take up the rotative speed of the shaft. If there were no resilient elements in the drive assembly, the immediate effect of the sudden starting of the pinion would be disastrous, resulting, very likely, in stripping the teeth of the pinion and gear. However, when axial movement of the pinion is prevented by the stop, the sleeve 4 and casing 19 immediately cease rotation and the motor shaft screws into the nut 15, thereby causing it to travel inwardly along the motor shaft against the expansive force of the coil spring until it finally comes in contact with the outer end of the sleeve 4. By this means, the shock of the sudden start is obviated and the pinion assumes the speed of the motor shaft through a gradual increase in the applied force, the greater part of the shock being taken up by the coil spring.

In the event that the pinion 6 fails to properly mesh with the gear, the sleeve will travel bodily outward, carrying the casing 19 with it, against the compression of the spring. This will permit sufficient rotation of the pinion, so as to cause it to properly mesh with the gear and prevent any disastrous effects.

It should be particularly noted that the spring in this driving assembly is not in a direct line of transmission, but serves merely to absorb the shock due to sudden impression

of the load on the pinion. There is, therefore, no tension upon the spring which operates under compression only, thereby lessening to a marked degree the chances of failure in operation of the mechanism.

I am aware that the specific embodiment of my invention herein shown and described is susceptible of considerable variation without departing from the spirit of my invention, and, therefore, I desire to claim the same broadly as well as specifically, as indicated by the appended claims.

Having thus described my invention, what I claim as new and desire to secure by Letters Patent is:—

1. In a driving mechanism for starting motors, the combination of a gear operatively connected to an engine; a driving shaft, the outer portion of which is threaded; a threaded sleeve on said shaft, having a grooved outer portion; an internally threaded pinion on said sleeve adapted to move axially on said sleeve into engagement with said gear; an internally threaded nut adapted to engage the threaded portion of said shaft; a casing forming a guide for said nut, having its inner end flanged to form a bearing on the sleeve and to engage said grooved outer portion; a coiled spring intermediate the nut and the flanged end of said casing; and means for limiting the axial movement of the nut.

2. In a driving mechanism for starting motors, the combination of a gear operatively connected to an internal combustion engine; a driving shaft, the outer portion of which is threaded; a nut having threaded engagement with the threaded portion of the shaft; an externally threaded sleeve mounted on the shaft, the outer end of said sleeve serving as a limiting stop for the nut; a casing inclosing the threaded portion of the shaft, the inner end of which has lugs bearing on and in engagement with the sleeve and the outer end of which has keyways cut on its inner surface forming a bearing for the nut; a spring interposed between the nut and the end lugs of the casing; and a pinion having threaded engagement with the sleeve and movable axially into enmeshment with said gear.

3. In a driving mechanism for starting motors, the combination of a gear operatively connected to an internal combustion engine; a driving shaft, the outer portion of which is threaded; a nut having threaded engagement with the threaded portion of the shaft; an externally threaded sleeve mounted on the shaft, the outer end of said sleeve serving as a limiting stop for the nut; means forming a driving connection between said sleeve and said nut, the nut having an axial sliding engagement with said means; a spring on said shaft adapted to yieldingly oppose the axial movement of said nut; and a pinion having threaded engagement with said sleeve and

adapted to move axially into engagement with said gear.

4. In a driving mechanism for starting motors, the combination of a gear operatively connected to an engine; a driving shaft, the outer portion of which is threaded; a threaded sleeve on said shaft, having a grooved outer portion; an internally threaded pinion on said sleeve adapted to move axially into and out of engagement with said gear; an internally threaded nut engaging the threaded portion of said shaft; a casing forming a guide for said nut, having its inner end flanged to form a bearing, and to engage said grooved outer portion of said sleeve; a coiled spring intermediate said nut and the flanged end of said casing; and means for limiting the axial movement of the nut.

5. In a driving mechanism for engine starting motors, the combination of a driving shaft, a driven shaft freely mounted upon the driving shaft, a pinion having a threaded mounting on said driven shaft and movable relative to the driven shaft into engagement with the engine member, a casing slidably mounted on said driven shaft, and a slidable connector forming a driving connection between the driving shaft and casing, said connector having a screw threaded bearing on the driving shaft.

6. In a driving mechanism for starting motors, the combination of a driving shaft, a driven shaft freely mounted upon the driving shaft, a pinion having a threaded mounting on said driven shaft and movable axially relative to the driven shaft into engagement with the engine member, a casing slidably mounted on said driven shaft, a slidable connector between the driving shaft and casing having a screw threaded mounting on the shaft, and resilient means normally tending to resist slidable movement of said slidable connector and casing, said connector forming a driving connection between the casing and shaft.

7. In a driving mechanism for starting motors, the combination of a driving shaft, a driven shaft freely mounted upon the driving shaft, a pinion operatively mounted on and adapted to be rotated by said driven shaft movable axially relative to the driven shaft into engagement with the engine member, a casing slidably mounted on said driven shaft, a slidable connector forming a driving connection between the driving shaft and casing having a screw threaded mounting on the shaft, and resilient means normally tending to resist slidable movement of said slidable connector and casing, the end of said driven shaft forming a limiting stop for movement of the slidable connector.

8. In a drive mechanism, a driving shaft having a threaded portion, a driven shaft freely mounted on the drive shaft, a pinion mounted on said driven shaft, a member op-

eratively connected to the driven shaft, and a connecting member having screw-threaded engagement with the threaded portion of the drive shaft and slidable engagement with the first named member.

9. In a drive mechanism, a drive shaft, a driven shaft, a pinion mounted on and movable on said driven shaft adapted to be rotated thereby, and a plurality of separate sliding members interposed between said driving and driven shafts, one of said members being axially slidable relative to the other member and having a screw threaded connection with the drive shaft.

10. In a drive mechanism, a drive shaft, a driven shaft, a pinion mounted on and movable on said driven shaft adapted to be rotated thereby, a plurality of separate sliding members interposed between said driving and driven shafts, one of said members being axially slidable relative to another, and both members being movable relative to the drive shaft, one of said members having a screw threaded mounting on the drive shaft.

11. An engine starter comprising in combination, a plurality of threaded elements; driving means for one of said elements; a pinion carried by the other of said threaded elements; a member connecting said threaded elements, said member having a lost motion connection with one of said elements; and means including a spring cooperating with said member to form a yielding driving connection.

12. An engine starter comprising, in combination, a driving shaft having a threaded portion; a relatively movable member cooperating with the threaded portion of said driving shaft; an independent threaded element; a pinion adapted for longitudinal and rotary movement carried by said threaded element; a resilient element interposed between said member and said threaded element for establishing yielding driving connection between said driving shaft and said threaded element.

13. An engine starter comprising, in combination, a driving shaft; a member carried by said shaft and movable thereto; a threaded sleeve carried by the shaft; a pinion adapted for longitudinal and rotary movement supported upon said sleeve; a cylindrical element connecting said member and said threaded sleeve, and means including a resilient element interposed between said member and said element for establishing a yielding driving connection therebetween.

In testimony whereof, I affix my signature.
CLARENCE F. GILCHRIST.
